UNITED STATES PATENT OFFICE.

ROBERT B. PRICE, OF STONEHAM, MASSACHUSETTS.

BOILER-TUBE BLOWER.

1,057,980.

Specification of Letters Patent.

Patented Apr. 1, 1913.

Application filed October 24, 1912. Serial No. 727,486.

To all whom it may concern:

Be it known that I, ROBERT B. PRICE, a citizen of the United States, residing at Stoneham, in the county of Middlesex and 5 State of Massachusetts, have invented new and useful Improvements in Boiler-Tube Blowers, of which the following is a specification.

This invention relates to improvements in 10 boiler tube blowers and is particularly adapted for use in connection with the horizontal return tube type of boiler.

The object of the invention is to provide 15 a blower adapted to blow soot, scales or ashes from the tubes of a boiler by directing a jet of superheated steam into the end of each of said tubes, said device being arranged as a fixture on said boiler and connected in such a manner to the door of said 20 boiler that it may be automatically moved out of the way by the opening of said door, whereby access may be had to the front tube sheet, without disconnecting said blowing device.

25 A further object of the invention is to provide a blower comprising nozzles directed toward or into the ends of the tubes of a boiler and by which one of the rows or series or a plurality of series of said tubes 30 may be blown, or the entire series may be simultaneously blown as desired.

Still another object of the invention is to provide means accessible from the exterior of the door of said boiler adapted to 35 control the nozzles of each of the series thereof.

The invention consists in the combination, 40 and arrangement of parts whereby the above objects and certain other objects hereinafter appearing are attained as set forth in the following specification and particularly pointed out in the claims.

Referring to the drawings: Figure 1 is a 45 front view of a boiler with the device embodying my invention shown in connection therewith, portions of said boiler being broken away to save space in the drawings.

Fig. 2 is a plan section taken on line 2, 2 of Fig. 1. Fig. 3 is a sectional elevation 50 taken on line 3, 3 of Fig. 1. Fig. 4 is a detail sectional view of one of the valves which controls one of the several series of nozzles.

Like numerals refer to like parts throughout the several views of the drawings.

55 In the drawings, 5 is a boiler preferably of the horizontal return tube type, 6 the

front tube sheet and 7 the tubes secured in said tube sheet. The front wall 8 of the boiler 5 is placed at a substantial distance from the front tube sheet 6 forming a chamber 9 through which the products of combustion from the fire tubes 7 pass to a chimney in the manner well-known to those skilled in the art.

In order that access may be had to the 65 chamber 9 and tubes 7 the boiler is provided with an opening 10 which is preferably closed by doors 11 and 12, although but a single door might be employed without departing from the spirit of the invention. 70 The door 11 is hinged at 13 upon one side of the opening 10, while the door 12 is hinged at 14 upon the opposite side of said opening, said door 12 being provided with a lip 15 which overlaps the edge of the door 75 11 and seals the front of said boiler when said doors are closed.

Within the chamber 9 at the front of the tube sheet 6 are arranged a plurality of nozzles 16 one for each of the tubes 7, said 80 nozzles alining with said tubes, or in other words, directed toward or into the open ends thereof.

Different boiler makers have adopted various methods of arranging the fire tubes in 85 boilers, some of which are arranged in zig-zag or staggered form, others being arranged in vertical rows, some in horizontal rows, and still others in both horizontal or vertical rows as is the case in the boiler 90 shown in the drawings and to facilitate the blowing of a boiler, the nozzles alining with the tubes of one row either vertical or horizontal, preferably the latter, are connected to one feeder 17, while all of said feeders 95 are in turn connected to a header 18.

The feeders 17 are arranged within the chamber 9 adjacent to the inside of the face of the doors 11 and 12 and are each connected through nipples 19 extending through 100 holes 20 in the door 11 to the header 18 which is arranged exteriorly of said door 11, said nipples constituting supports for the feeders 17 and nozzles 16. A supply pipe 21 connected to said header 18 extends 105 along the front of said boiler to the pivots 13 of the door 11 and at which point in said supply pipe a pivotal connection 22 is provided, the axis thereof alining with the axes of the pivots 13, whereby said door 11 may 110 be swung upon its pivot without disturbing the connections for said tube blowing device.

Many types of nozzles may be employed in a device of this character, but I preferably employ tubes much smaller in diameter than the feeders 17 and which are secured at one of their ends to said feeders, while their opposite ends terminate at a slight distance from the ends of the tubes 7, the differences in diameter of said tubes resulting in a jet of steam of small volume, but of increased velocity the effect of which on the interior of the tubes 7 is to quickly remove all scales, dust or soot therefrom and to polish the interior surface thereof, performing this operation in a very short time. Furthermore by inclosing the nozzles 16 within the chamber 9, said nozzles may be operated while the boiler is in operation and the passage through said nozzles being very small and of quite a substantial length, the steam passing therethrough will be exposed to the heat passing through the chamber in which said nozzles are located, consequently the jet of steam discharged from said nozzles will be superheated and this being dry no injury will result from the contact thereof with the tubes of the boiler, nor will the fire be checked thereby to any extent.

By the arrangement of the nozzles 16, there being one for each of the tubes of the boiler and all of said nozzles being connected through their feeders 17, header 18 and supply pipe 21, all of said tubes may be blown simultaneously although such a method is not always practical owing to the amount of steam discharged into said boiler which is apt to clog the same and retard the discharge of the soot and scales. The preferred method therefore is to blow one row or series of tubes at a time and this being accomplished while there is a fire in the boiler, the escaping gases generated thereby will assist in the carrying off of the soot or scales from the tubes being blown. To facilitate the blowing of the various series of tubes, valves 23 are provided at the juncture of each of the nipples 19 with the header 18 as shown in Fig. 4 and by the manipulation of said valves 23 the series of nozzles controlled thereby may be shut off from the header 18 without in any way affecting the flow of steam through said header to the other feeders and their respective nozzles, said valves being arranged exteriorly of the door 11 whereby the same may be operated at will even though a fire may be going in the boiler.

As hereinbefore stated the feeders 17 are parallelly arranged adjacent to the inner faces of the doors 11 and 12, while the header 18 is arranged exteriorly of and adjacent to said door 11, said header 18 and feeders 17 being connected by the nipples 19 which pass through the holes 20 in said door and to positively secure said feeders 65 and said header in their respective posi-

tions relatively to said door, collars 24 are placed preferably upon the upper and lower nipples between the valves 23 and the outer face of the door 11, while a boss 27 formed upon the door 11 performs this function at 70 an intermediate point, and washers 25 are inserted between the T's 26 and the inner face of said door, the T's 26 being firmly secured on the nipples 19 against the washers 25. In this way it will be seen that the 75 blowing device becomes a fixture of the boiler with the ends of the nozzles 16 always in position when the doors 11 and 12 are closed so that at any time the same may be operated to blow out one series or the 80 entire series of the tubes as desired, the only operation necessary to accomplish this being to manipulate the valve or valves controlling the particular series of nozzles through which it is desired to discharge 85 steam.

When it is necessary to get at the front tube sheet or the ends of the tubes to inspect or repair the same the door 12 is first swung upon its pivot 14 until clear of the 90 ends of the feeders 17 after which the door 11 will be swung upon its pivots 13 until the nozzles 16 carried thereby are entirely removed from the chamber 9.

Having thus described my invention, 95 what I claim and desire by Letters Patent to secure is:

1. The combination with a fire tube boiler having a door formed in two parts and pivoted upon opposite sides of said boiler, of a 100 nozzle directed into the end of each of the tubes of said boiler, feeders for said nozzles arranged inside of said doors, a header arranged upon the outside of said doors, nipples extending through one of said door 105 parts connecting said feeders with said header and constituting supports for said nozzles, a valve interposed between the end of each of said nipples and said header, and a flexible supply pipe connected with said 110 header adapted to maintain said nozzles in operative connection therewith during the swinging of the door upon which said nozzles are mounted, upon its pivot.

2. The combination with a boiler having 115 a plurality of parallel series of tubes, and a door pivoted at one end of said tubes, of a tube blower secured on said door and movable therewith, comprising a plurality of series of nozzles, one of said nozzles being 120 directed into the end of each of said tubes, and valves arranged upon the outside of said door adapted to control said series of nozzles respectively.

3. The combination with a boiler having a 125 plurality of fire tubes, of a tube blower comprising a steam supply pipe, feeders connected with said supply pipe, a nozzle directed toward each of said fire tubes, said nozzles being secured in said feeders and of 130

- relatively smaller diameter than said feeders and valves for controlling the flow of steam from said supply pipe into said feeders respectively.
- 5   4. The combination with a boiler having a plurality of fire tubes, of a tube blower comprising a steam supply pipe located outside of said boiler, feeders connected with said supply pipe and located upon the interior of
- 10 said boiler, a nozzle directed toward each of said fire tubes, said nozzles being secured in said feeders and of relatively smaller di-
- ameter than said feeders and valves operable from the exterior of said boiler for controlling the flow of steam from said supply pipe 15 into said feeders respectively.
- In testimony whereof I have hereunto set my hand in presence of two subscribing witnesses.

ROBERT B. PRICE.
